COIN HANDLING APPARATUS

Robert F. Broussard, Houston, Tex., and Lester D. Sollenberger, Chicago, Ill., assignors, by direct and mesne assignments, to Duncan Parking Meter Corporation, Chicago, Ill., a corporation of Illinois

Application July 17, 1948, Serial No. 39,266

23 Claims. (Cl. 194—72)

1

This invention relates in general to a coin handling apparatus of which a parking meter is one exemplification. Although in certain of its aspects it is applicable to coin mechanisms of various kinds, the ensuing description will be directed to a parking meter as a suggestive example of mechanism for which this invention is particularly useful.

One of the more important objects of the invention is to provide a coin-actuated or coin-controlled mechanism wherein the coin is deposited and the mechanism energized and triggered in a single continuous operation, and wherein the manual force needed to energize the mechanism is applied to a movable element of considerable surface area so that it is not necessary for a patron to exert a substantial amount of pressure on the coin itself.

In the operation of parking meters, for example, it is desirable to avoid the need for a motor spring which must be manually wound periodically by a service attendant; and it also is desirable to avoid resort to electric power and the heavy expense of installing power lines for this same purpose. The only alternative is a mechanism which must be manually energized by each user in turn, as by winding a spring each time a coin is deposited. Such an operation tends to complicate the manipulation because it has heretofore involved, first, the deposition of a coin and, secondly, the turning of a knob or the pulling of a lever to wind the motor spring.

With the view to avoiding any such two-stage operation, it has heretofore been proposed to make use of each deposited coin as a medium for applying the pressure necessary to energize the meter mechanism. Such a procedure has proved quite satisfactory save for the fact that the meter-energizing pressure must, as a practical matter, be applied to the edge of the coin which has only a small area to receive pressure from the finger of the user.

A more satisfactory arrangement is afforded by the present invention in that the manually applied meter-energizing force is exerted, not against the coin but, instead, against an element having an extended finger-engaging area in which the coin-receiving slot is formed. In achieving that objective we have encountered a number of major problems the solution of which involves certain inventive features hereinafter to be described.

Another object of this invention is to expedite the servicing of coin mechanisms employing driving springs which sometimes fail and have to be

2

replaced. And to that end we have provided a spring unit which can quickly be detached and replaced, when the need arises, without the necessity of disturbing the remainder of the coin mechanism or of taking the mechanism to a service shop.

Additional objects and advantages inherent in this invention will be pointed out as the ensuing detailed description progresses.

10 Referring to the drawings which accompany this specification:

Figure 1 is a small scale front elevation of a coin mechanism such as a parking meter;

15 Fig. 2 is an enlarged side elevation of the coin mechanism, viewed from the left-hand side of Fig. 1;

Fig. 3 is an enlarged side elevation, viewed from the right-hand side of Fig. 1;

20 Figs. 4 and 5 are exploded isometric views illustrating the principal components of the coin mechanism in spaced relationship, Fig. 5 being, in fact, a part of Fig. 4, but separately identified to facilitate description;

Fig. 6 is an axiswise sectional view of the assembled mechanical components which are concentric with the main axis and shown isometrically in Fig. 4;

Fig. 7 is a rear view of the coin selector, together with certain parts mounted thereon or immediately associated therewith;

25 Figs. 8, 9 and 10 are fragmentary views depicting successive stages in the operation of the coin selector and of the transmission mechanism for rotating the coin-carrier in response to actuations of the coin selector, the coin receiving and inducing member, for convenience, being shown at the limit of its inward movement in Fig. 10;

30 Figs. 11-14 inclusive are successive views taken at line 11—11 of Fig. 3, depicting the action of the cam mechanism which serves to retract the movable bridge member and coin gauge, the coin gauge in Fig. 13, for the purpose of clarity, being shown slightly spaced from but in position to ride upon the cam disc;

35 Figs. 15-17 inclusive are successive views taken at line 15—15 of Fig. 3, illustrating the operation of the coin-carrier;

40 Fig. 18 is an isometric view of the movable bridge member; and

45 Fig. 19 is an isometric view of the coin gauge. The coin mechanism illustrated is a self-contained timing unit designed to be removably inserted, as a whole, in a housing (not shown) which affords protection against the weather and vandals, and contains a receptacle (not shown)

to receive the coins as they drop from the bottom of the mechanism.

The various mechanical parts of the coin mechanism are supported by a frame 20 consisting principally of parallel front and back plates A and B and an intermediate plate C, secured together in laterally spaced relation by means of six dowel pins 21-26 inclusive which extend through various tubular spacer sleeves 27-38 inclusive and are threaded internally at both ends to engage fillister head machine screws 39 the threaded shanks of which pass through clearance holes formed in the front and back plates A and B. The frame is adequately rigid in all directions to hold the mechanical parts in proper alignment.

An axis α extending perpendicularly of the three plates A, B and C constitutes the center of rotation of the several mechanical components including a tubular sleeve 40 which is journaled in the front plate A, and a main shaft 41 which is journaled in the intermediate plate C and in the bore of the sleeve 40. The sleeve 40 and shaft 41 are not drivably intercoupled but, on the contrary, are relatively rotatable about the axis α .

For a parking meter we provide a timing or speed-control mechanism E in the form of a fly train which is positioned between the plates B and C. This fly train, which is coupled to the rear end of the shaft 41, serves to determine the rate of rotation thereof so that the meter indicator will traverse the scale of a dial F when registering elapsed time in whatever unit of time may be assigned per complete timing operation, as, for example, one hour.

The sleeve 40 has a diametric end slot 42 which engages the inner end of a spiral spring 43 the function of which is to bias this sleeve rotationally and to store up the manually supplied energy required to drive the meter mechanism. The spring 43 is readily withdrawable from the slot 42, and its outer end is riveted or otherwise anchored to a cup-like housing 44 the cavity of which is proportioned to receive the spring. The spring housing 44 has an external flange 45 provided with a number of peripherally spaced notches 46 which are adapted to register with and clear the heads of two flanged pins 47 which are secured to and project outwardly from the front plate A at opposite sides of the axis α . The flanges or heads of the pins 47 are appropriately spaced from the front face of the frame plate A so that they overlie the flange 45 when the spring housing is put in place, as shown in Fig. 3, and then rotated through a small angle. The heads of the pins 47 then serve to anchor the spring housing 44 against the front plate A while permitting quick and easy detachment.

The spring 43 is the part most likely to need replacement short of the normal life of a meter mechanism, and the construction here shown and described makes it not only possible but easy to replace such a spring without the necessity of any disassembly or of taking the meter mechanism to a repair shop. This constitutes one of the novel features of our invention.

Affixed to the sleeve 40 and rotatable therewith is a power arm 50 including an integral partial gear 51 and a laterally projecting latch pin 52. The partial gear 51 is in mesh with the teeth of a gear segment 53 which is pivoted on the dowel pin 24 (see Fig. 8) and provided with a clearance notch 54 the purpose of which will later be explained.

Also pivotally mounted on the dowel pin 24 is a lever arm 60, constituting a coin receiving and inducting member, herein termed the coin selector, having a coin slot 61 dimensioned to receive coins of a particular denomination, such as five-cent pieces. This coin selector may conveniently be a casting or a formed sheet metal part, and desirably is provided with a front concavity 56 designed to accommodate the end portion of the finger of the coin depositer, as most clearly shown in Fig. 5. The coin selector is also recessed at the rear to receive the additional parts shown in Fig. 5. The front concavity 56 provides a seat for centering the finger or thumb which releases and pushes a coin into and through the slot 61, as depicted in Fig. 16, and it also aids in bringing the coin into line with this slot. On these accounts it is a desirable but not an indispensable feature.

The additional parts shown in Fig. 5, and previously referred to as such, comprise a rocker member 62, a pivot screw 63 therefor, a dog 64, a leaf spring 65 for biasing said dog, and a second pivot screw 66 by means of which the dog 64 and the spring 65 are pivotally mounted on the coin selector. The rocker member 62 has two parallel, laterally spaced arms 62a and 62b which are drilled to receive the pivot screw 63 whereby the rocker member is rotatably mounted on the coin selector 60 within the rear cavity thereof. The arm 62b is positioned in alignment with the slot 61 (see Fig. 7) and is so situated that its lower end, which is suitably beveled, is adapted to be engaged by the upper edge portion of a proper size incoming coin (see Fig. 9) in such manner that the coin rotates the rocker member counter-clockwise through a small angle from the posture which it normally assumes, as per Fig. 8.

The arm 62a has a laterally turned ear 62c which normally is engaged by a lug 64a on the distal end of the dog 64, as shown in Fig. 8; and the pressure exerted by the spring 65 on the dog 64 is sufficient to cause adherence between the end of the lug 64a and the ear 62c so that the rocker member will retain the posture in which it is shown in Fig. 8 until a coin is brought to bear against the arm 62b, as depicted in Fig. 9. The rocker member 62 is loosely mounted on the pivot screw 63 and the movement of the rocker member under the influence of gravity about the pivot screw 63 is sufficient to overcome the pressure of the spring 65 of the dog 64. When the rocker member 62 is in the posture of Fig. 8, the ear 62c is aligned with the notch 54; and if the coin selector 60 is depressed from the posture of Fig. 8, without inserting a coin, the ear 62c will enter the notch 54 but will be ineffective to move the gear segment 53. But if, on the other hand, a coin of the proper size is inserted in the coin slot 61, the rocker member 62 will be rotated thereby, counter-clockwise and to such an extent as to cause the ear 62c to move to a position wherein it can engage the adjacent edge of the gear segment 53 just above the notch 54. The same rotary movement of the rocker member 62 which places the ear 62c in position to engage the gear segment 53 also moves the said ear relatively to the distal end of the dog 64 so that said dog can rotate slightly in the clockwise direction, as viewed in Figs. 8 and 9, under the impetus of its biasing spring 65. This places one edge of the ear 62c in a notch 64b formed in the distal end of the dog 64 just above the lug 64a. When thus engaged with the ear 62c of the

rocker member 62, the dog 64 functions as a backing member or abutment for the ear 62c, and thus serves to hold the rocker member against rotation and in a position such that the force applied to the coin selector by the user's finger is transmitted through the rocker member 62 and its ear 62c to the gear segment 53.

It will be clear that when a proper coin is inserted in the coin slot 61 and the coin selector 60 is depressed, the gear segment 53 will be engaged by the ear 62c and rotated; and that the gear segment 53 transmits rotation to the power arm 50 so that the latter is rotated clockwise, as viewed in Fig. 8, to the posture in which it is shown in Fig. 10. If the coin selector 60 is depressed without inserting a coin, the ear 62c will not engage the gear segment 53 but will, instead, move through the notch 54.

Assuming that a blade or thin tool is inserted through the coin slot 61 to trip the rocker member so as to condition it for engagement with the gear segment 53, nothing will come of such an effort. Any such attempted operation is ineffective to retract the meter indicator finger and, therefore, accomplishes nothing. Insertion of a proper size coin into the coin slot, but with the coin not released, will also produce a tripping of the rocker member and rotation of the power arm; but such operation is likewise ineffective to retract the meter indicator finger.

Mounted on the sleeve 40 and rotatable independently thereof is a bushing 70 forming the hub of a coin carrier 75 one function of which is to receive and transfer the coins from the coin selector slot to a discharge passageway through which the coins travel enroute to a coin receptacle. Another function of the coin carrier 75 is to shift the time indicator finger whenever a coin of proper size is present in the carrier. Its ultimate purpose is to prevent the meter mechanism being re-set unless a coin or token of the requisite diameter has been deposited, and to assure the accomplishment of that object when, in fact, a proper coin has been deposited.

The coin carrier as a whole is shown most clearly in Fig. 4. It consists principally of two parallel plates 76 and 77, separated laterally by a spacer 78 to an extent sufficient to admit therebetween a coin of the proper denomination. The two plates 76 and 77 are substantially identical at the right-hand side of the axis a, as viewed in Fig. 4; but at the left-hand side of the axis they differ in that the plate 76 includes a stop arm 79 while the plate 77 includes a toothed sector 80 which serves as an escapement wheel. An arcuate plate 81 (see Fig. 11) is riveted or otherwise attached to the far side of the plate 77 and has a series of peripheral teeth identical with those on the plate 77 but in staggered relation thereto.

A retractable bridge member 82, detailed in Fig. 18, is positioned between the two plates 76 and 77 and forms a part of the coin carrier. This bridge member has an aperture at 83 (Fig. 18) through which passes a pin 84 by means of which it is pivotally attached to the coin carrier plates. The function of the bridge member is to provide a path for the passage of coins, one at a time, from the coin selector slot to the interior of the coin carrier; and it serves also as the peripheral wall of a pocket inside the coin carrier, in which pocket the coins are retained, one at a time, while the coin carrier is in rotation to deliver the coin from the coin slot to a discharge chute which will later be described. It will be observed that the bridge member 82 has a semi-circular concave edge surface 85 which terminates at one end

in a flat edge surface 86. The concavity 85 is of a radius slightly larger than that of the coins to be received; and the flat surface 86 functions as a bridge over which the coins roll or slide in passing from the coin slot 61 into the coin carrier pocket defined laterally by the plates 76 and 77 and peripherally by the curved surface 85. The bridge member 82 is biased rotationally by a coil spring 87 so that normally it projects outwardly from the body of the coin carrier, as shown in Figs. 4 and 11.

The coil selector 60 is normally biased outwardly by a spring 90 (Figs. 3 and 4) so that it assumes the posture in which it is shown in Fig. 11, this being its outward limiting posture as determined by a stop screw 91 (Figs. 1 and 5) which is carried by the selector and projected into a slot 92 in the front frame plate A. The inward limiting posture of the coin selector, shown in Fig. 10, is determined also by the pin 91 and the rear end of the slot 92. Another arcuate slot 89 in the front plate A is provided to clear the lower flange of the coin selector.

From Fig. 11 it will be seen that the distal end of the bridge member 82 normally extends across enough of the gap between the coin selector 60 and the body of the coin carrier to prevent the coins dropping down through said gap. As each coin is pushed in through the coin slot it presses against the bridge member 82, causing the latter to be retracted into the body of the coin carrier and against the opposition of the spring 87. The bridge member 82 is provided with a curved arm 88 forming a tail-piece the purpose of which is to effect retraction of the bridge member into the body of the coin carrier independently of pressure from any coin. This will be explained at a later point.

Also pivotally mounted on the pin 84 and forming a part of the coin carrier is an element 95 which we will refer to as a coin gauge. This element, detailed in Fig. 19, includes two arms 96 and 97 extending from the pivotal center 98. The former arm is bent at its free end to form a laterally projecting portion 99 having a notch 100 of a width slightly greater than the thickness of the coins which the meter is designed to receive. The arm 96 also has a laterally turned lug 101, the function of which will presently be made clear. The end portion 99 extends across the body of the coin carrier, laterally of the plates 76 and 77 as will readily be apparent from Fig. 4, and the two plates 76 and 77 are arcuately slotted, as at 102, to clear the end portion 99, thus allowing said portion to be pushed back into the body of the coin carrier as the coin gauge is rotated from the normal posture in which it is shown in Figs. 4, 11 and 12. When a coin passes through the coin slot 61 and onto the bridge member 82, the coin edge portion enters the notch 100 in the coin gauge to push the end portion 99 back into the body of the coin carrier, thereby rotating the coin gauge 95 about its pivotal center, against the opposition of a coil spring 93 (see Fig. 11) similar to the spring 87 which acts on the bridge member 82. A notch 104 is cut in the bridge member 82 to clear the end portion 99 of the coin gauge.

The primary function of the coin gauge 95 is to prevent the meter being operated effectively without using a proper coin or token; and it accomplishes that end by virtue of the fact that it requires the presence of a coin or token

of prescribed diameter in the coin carrier in order to hold the lug 101 (Fig. 19) in a position wherein it can engage a driven element through the actuation of which the time indicating finger is moved to the starting point. An additional function of the coin gauge is to eject deposited coins or token in the event that a depositor should fail to depress the coin selector far enough to re-set the meter, or in the event of any mechanical failure which might otherwise result in a depositor giving up his coin or token without being able to put the meter into operation.

Referring more especially to Figs. 15-17 inclusive, when the gear segment 53 is rotated, as a result of fully depressing the coin selector 60 with a proper coin inserted in its slot 61, the latch pin 52 carried by the power arm 50 is moved in an arcuate path through an angle of about 90° and is thereupon engaged by a spring-pressed latch 106 which is pivotally mounted, by means of a screw 107, on the coin carrier 75. This results in the coupling together of the power arm 50 and the coin carrier 75 so that, when the segment 53 is thereafter released and the power arm 50 is consequently returned to its normal posture by the spring 43, the coin carrier 75 will be rotated back with it. That is to say, the coin carrier will rotate with the power arm 50 through a distance of about 90° as a result of the latch pin 52 being engaged by the latch 106.

Immediately after the coin selector 60 has been depressed sufficiently to permit the latch pin 52 to be engaged by the latch 106, the dog 64 will strike a stop pin 110 which projects inwardly from the front frame plate A and stands in the path of the dog; the dog 64 will thereupon recede from the posture in which it is shown in Fig. 9, thereby releasing the lug 62c of the rocker member 62 from the notch 64b on the dog, thus allowing the rocker member 62 to rotate to such an extent that the lug 62c is brought into alignment with the notch 54 on the gear segment 53. The latter is then free to return to its initial posture. In Fig. 10 the power arm 50 is shown as about to return to its starting point (Fig. 8) and as latched to the coin carrier which will rotate with the power arm.

A coil spring 111 (see Figs. 4 and 6) encircling the hub of the power arm 50 is anchored at one end to said power arm and at the other end to the stop arm 79 of the coin carrier. This spring is tensioned to bias the coin carrier toward its normal posture, and is effective when the coin carrier is released from the power arm to return it to normal posture. Release of the power arm from the coin carrier is effected when the angular surface 106a of the latch 106 engages a latch-releasing pin 112 which is mounted on the front plate A. This pin which is located in alignment with an arcuate slot 113 is clamped to the frame plate A by means of a screw 114 (see Fig. 1). It is movable along said slot and is, therefore, adjustable positionally so as to enable variation of the angle of rotation of the coin carrier.

Successive stages in the rotational movement of the coin carrier are depicted in Figs. 15-17. In Fig. 15 the coin carrier and coin selector are shown in their normal postures, and a coin L, inserted in the coin slot, is shown resting on the bridge member 82 and against the coin gauge 95. In Fig. 16 the coin selector is shown fully de-

pressed as it would appear when a depositor's finger 115 is in engagement with the front of the coin selector and with the edge of the coin. Here it will be seen that the coin L has been pushed in and has caused the bridge member 82 and the coin gauge 95 to recede into the body of the coin carrier. Also it will be seen that the power arm 50 has moved counter-clockwise to such an extent that the latch pin 52 is engaged by the latch 106, and the power arm, together with the coin carrier, is about to rotate in the clockwise direction. In Fig. 17 the clockwise rotation has been completed and the latch 106 has come into engagement with the pin 112 which has moved the same to disengage it from the power arm. The coin L has also been advanced to a foremost position where it is freed for gravity descent into a chute structure presently to be described. At this point the coin carrier is free to reverse its movement so as to return to its normal posture (Fig. 15) under the impetus of the spring 111.

If the movements of the coin carrier were not in some way restrained, they would occur so violently as to cause a good deal of noise and possible damage to the mechanism, and for that reason there has been provided a speed limiting or restraining mechanism in the form of an escapement. This comprises the two sectors 80 and 81, the teeth of which are mutually staggered, and two escapement oscillators 116 and 116' which are mounted on a shaft 117 the two ends of which are secured to the frame plates A and C, respectively. Each escapement oscillator includes a pair of detents 118, 119, which are positioned to be engaged alternately by the teeth of the sectors 80 and 81, so that the two oscillators are rocked non-synchronously by the sector teeth. In consequence, the aggregate inertia of these oscillators is sufficient to impose a desirable degree of restraint on the speed of rotation of the coin carrier. The latter rotates quite rapidly notwithstanding the restraint imposed by the escapement mechanism, but not fast enough to give rise to excessive noise when brought to a stop, nor to cause injury to any of the meter parts. The shaft 117 serves, additionally, as an abutment for the stop arm 79 which forms an integral part of the coin carrier 75 (see Fig. 15).

The same degree of restraint on the speed of rotation of the coin carrier could be obtained with only one oscillator of greater mass than that of either of the two oscillators 116, 116' and with only one toothed sector; but it has been found that smoother action is obtainable by resorting to the use of two oscillators having the characteristics noted.

A coin chute structure 122 which is supported on the dowel pins 22 and 25 is located below the coin carrier 75. This structure provides an arcuate track 123 which is homocentric with the coin carrier 75, and a vertical enclosed passageway 124 through which the coins drop from the coin carrier when the latter has rotated from the normal posture of Fig. 15 to the alternate limiting posture of Fig. 17. The function of the track 123 is to hold the coin within the pocket of the coin carrier during the clockwise rotation of the latter, as depicted in Figs. 15-17.

It is common practice to so construct parking meters that the last-deposited coin or token is visible through a window provided for that purpose, the object being to discourage the use of slugs; and to accomplish that end it is necessary to interrupt the passage of each coin enroute from the meter mechanism to the coin receptacle

situated therebelow. Accordingly, there is provided in the coin chute structure 122 a circular window 125, in line with which each descending coin is stopped and held until the next succeeding operation of the meter, following the deposit of another coin.

A bellcrank 127 is pivotally mounted on the coin chute structure 122 by means of a pivot screw 128 (see Fig. 15), and comprises an upwardly extending arm 127a and a downwardly extending arm 127b. A small coil spring 134 biases said bellcrank counter-clockwise, as shown in Fig. 11, and clockwise, as shown in Fig. 15, so that it normally assumes the posture in which it is shown in those figures. The lower arm 127b has two laterally turned ears 129 and 130 which extend transversely of the coin chute structure. The ear 130 is so positioned that it is normally effective to intercept each coin as it moves downwardly through the coin passageway 124, and it is shown so functioning in Figs. 11 and 15. This ear 130 bears against a shoulder 131 on the coin chute structure which acts as a fixed stop to limit the rotation of the bellcrank 127.

The ear 129 normally stands outside the coin passageway 124, but is adapted to move into this passageway when the bellcrank 127 is rotated counter-clockwise from the position of Fig. 15 to that of Fig. 17. It will be observed from Fig. 17 that when the bellcrank 127 is so rotated the ear 130 is moved out of the path of the coin shown resting thereon in Fig. 15, and that the ear 129 is moved through an arcuate slot 126 in the coin chute structure to a position, as per Fig. 17, wherein it is effective to intercept a coin dropping from the coin carrier through the coin passageway 124. This is necessary in order to discharge the coin held by the ear 130 (see Fig. 15) without discharging the newly deposited coin.

Rotation of the bellcrank 127 from its normal posture (Fig. 15) to its alternate posture (Fig. 17) is effected by the lug 101 which forms an integral part of the coin gauge 95 (Fig. 19). If there is a coin in the coin carrier when the latter is rotated, as is normally the case, the coin gauge will be retracted so that the lug 101 is in a position to engage the end of the bellcrank arm 127a and thus rotate said bellcrank counter-clockwise, as clearly shown in Fig. 17. If, however, the coin carrier is rotated without a coin having been deposited (which can be done if the rocker member 62 is tilted by putting a coin in the coin slot and then withdrawing it), or by inserting some small thin instrument, the coin gauge will not be retracted sufficiently and its lug 101 will not be in a position to rotate the arm 127a sufficiently to release the coin being held by the ear 130. Accordingly, the coin at the window 125 will remain in that position until after another coin has been deposited in the meter. Hence, under normal operating conditions there is always a coin under retention at the window 125.

Assuming that the meter illustrated is designed to operate only on five-cent coins, the coin slot 61 would necessarily be large enough to receive pennies and dimes, since those are smaller coins, both as to thickness and diameter. The insertion of a coin of either of those denominations can be effective to tilt the rocker member 62 and thus make it possible to rotate the coin carrier and pass such coins into the coin passageway 124. They would not be effective, because of their inadequate diameters, to retract the coin gauge sufficiently either to re-set the meter or rotate the bellcrank 127 far enough to release the five-

cent coin being retained by the ear 130; and it is desirable that such unauthorized coins be returned in each case to the depositor. For that reason there is provided an edgewise slot in the coin chute structure at 132 through which pennies and dimes are ejected; and the ejection is accomplished by causing such coins to strike the five-cent coin under retention and thence bounce out through the slot 132. To that end there is 5 swingably mounted on the pivot screw 128 a triangular plate 133 which normally projects into the coin passageway 124 (see Figs. 11 and 15). This plate does not interfere with the normal downward passage of five-cent pieces because it 15 is light enough to swing out of the way under the weight of each such coin. But whenever said plate is struck by a descending penny or dime it deflects the coin enough so that it strikes the five-cent piece under retention at the side of its center toward the slot 132, thus causing the penny or dime to bounce in the right direction to pass 20 out through the slot 132.

With only the mechanism so far described, any attempted operation of the coin carrier in any 25 manner except by complete insertion of a coin of the prescribed diameter would result either in no retraction or insufficient retraction of the bridge member 82 and the coin gauge 95 to enable those elements to clear the coin chute structure. This 30 should be evident from inspection of either Fig. 11 or Fig. 15 wherein the bridge member and coin gauge are shown in their normal fully-extended postures. It is essential, therefore, to make provision for retracting the bridge member 35 and coin gauge into the body of the coin carrier whenever the coin selector 60 is depressed, irrespective of whether a coin of the proper denomination has been deposited. That end has been accomplished by means of a cam 135 which is 40 affixedly mounted on one end of the bushing 70 forming the hub of the coin carrier 75. This cam is rotatable independently of both the sleeve 40 and the coin carrier 75, and it consists of a disc 135a and a laterally projecting peripheral arcuate flange 135b; it also has a peripheral notch 135c adjoining one end of the flange 135b. A link 136 is pivotally connected at 137 to the cam disc 135a, and it also is pivotally connected at its other end to the coin selector 60 by means of a 45 pivot screw 63.

The tailpiece 88 on the bridge member 82 is 50 bent to pass around the edge of the adjacent side plate 77 of the coin carrier 75, as best shown in Fig. 4, and its distal end is situated within the notch 135c against the edge of the cam disc 135a 55 when the cam 135 is in its normal posture, as per Fig. 11. At the same time the distal end of the arm 97 which forms a tailpiece for the coin gauge 95 (which is not in line with the disc portion 135a of the cam) is not engaged by the flange 135b. Under those conditions both the bridge member 82 and the coin gauge 95 are fully 60 extended toward the coin selector 60.

It will be apparent that, by reason of the link 65 136, whenever the coin selector is depressed the cam 135 is rotated clockwise, as indicated in Fig. 12; and from Fig. 13 it will be seen that immediately after rotation of the cam has started, the tailpiece 88 is lifted by the cam, thereby rotating the bridge member 82 about its pivotal center 83 in the direction to retract the projecting end portion thereof into the body of the coin carrier where it is clear of the coin chute structure.

If a proper coin has been deposited in the coin

slot and is retained therein, under finger pressure while holding the coin selector 60 depressed, the coin gauge 95 will be retracted by the pressure of the coin thereagainst sufficiently to enable the coin gauge to clear the coin chute structure; but in the event no coin has been deposited and it has been made possible, in the manner previously explained, to depress the coin selector, the ensuing rotation of the coin carrier (which carries the coin gauge with it) will cause the tailpiece 97 of the coin gauge 95 to ride up onto the outer peripheral surface of the flange 135b, consequently rotating the coin gauge about its pivotal center 98 (see Fig. 14) so as to retract the arm 96 sufficiently to clear the coin chute structure. When the coin carrier has returned to its normal posture after going through a complete cycle of operation, the cam 135 releases the two tailpieces 88 and 97 and thus allows the bridge member 82 and the coin gauge 95 to reassume their normal postures.

If the meter is being operated with a proper coin or token, the cam 135 will have no effect on the coin gauge during the delivery half of the coin carrier cycle because the coin gauge is so far depressed by the coin that the end of its tailpiece is farther removed from the center of rotation of the cam than is the outer peripheral surface of the flange 135b. For that reason, when the coin carrier has reached the end of its delivery stroke the coin gauge is free to rotate clockwise to a limited extent, as viewed in Figs. 11-14, under the impetus of its restoring spring and is thus effective to propel the coin into the coin passageway 124.

A sleeve 140 on the main shaft 41 (see Fig. 6) is rotatable relatively to said shaft and forms the axial hub of an indicator plate 142 having an integral radially projecting finger 143 the free end of which registers with the time-calibrated scale of a dial plate F (see Fig. 1) which is supported at its two ends on the dowel pins 23 and 24 of the meter frame. A segmental pulley 146 (see Fig. 6) is fixedly secured to the back face of the indicator plate 142, coaxially therewith, and has a peripheral groove in which is seated a coil spring 147 one end of which is suitably anchored to the segmental pulley while the other end is anchored to the meter frame, as illustrated in Figs. 2 and 3. The spring 147 is tensioned so as to bias the indicator plate 142 and its finger 143 toward the zero end of the scale on the dial plate F which is at the left of the scale, as viewed in Fig. 1.

A fine-toothed ratchet wheel 150 is fixedly secured to the main shaft 41 (see Fig. 6) and is adapted to be engaged peripherally by a spring pawl 151 which is anchored at one end on a stud 152 secured to and projecting laterally from the indicator plate 142. The ratchet and pawl are so directed that the indicator plate 142 and its finger 143 can be rotated clockwise without rotating the shaft 41 and, therefore, without any restraint other than that imposed by the spring 147. But as soon as a clockwise rotation of the indicator plate has been completed, in the manner presently to be explained, and the indicator plate has subsequently been released, it will be returned to the zero position by the spring 147; but its return speed will be very slow, ordinarily requiring one hour to traverse the dial scale, because upon commencement of each return movement the pawl 151 is effective to drive the ratchet wheel 150 whose rotation is controlled by the fly train E.

Mounted on the front face of the indicator plate 142 and concentric therewith is a generally circular time-control plate 154. This is provided with an arcuate slot 155 through which extends a clamping screw 156 which is threaded into the indicator plate 142. Upon loosening of this clamping screw, the time-control plate can be rotated relatively to the indicator plate to the extent permitted by the arcuate slot 155. The peripheral margin of the time-control plate 154 is cut to form an arcuate notch 155a which terminates at one end in a radial shoulder 157 (see Fig. 4). The shoulder 157 is so positioned, radially of the axis α , that it is engageable by the lug 101 of the coin gauge 95 whenever the coin gauge is fully retracted into the body of the coin carrier as a result of the presence in the pocket of the coin carrier of a coin of the prescribed denomination. A coin of lesser diameter will retract the coin gauge, but not sufficiently to enable the lug 101 to engage the shoulder 157. The angular position of the shoulder 157 can be adjusted by rotating the time-control plate, but only after first loosening the clamping screw 156. This makes it possible to adjust the sweep of the time indicator finger so that it will register accurately with the dial scale graduations.

It will now be apparent that when the coin carrier 75 is rotated clockwise, as viewed in Figs. 15-17, it will carry with it the indicator plate 142 and finger 143, provided the coin in the pocket of the coin carrier is of the full prescribed diameter, but that it will not rotate the indicator plate when no coin has been deposited, nor when the deposited coin is of a diameter less than that of a prescribed coin.

The fly train E (Figs. 2 and 3) comprises a train of spur gears 160 and an escapement 161 including an escapement wheel from which is extended a wig-wag signal 162. Since the gear and escapement mechanisms may follow any of the usual constructions no further description thereof need be given. The escapement gear train which is driven from the rear end of the shaft 41 carries the wig-wag signal 162 to oscillate back and forth proximate to the arcuate dial plate F, and such eye-arresting movement affords a sure indication that the finger 143 is then in operation.

We claim:

1. The combination in a coin-controlled mechanism, of a coin selector comprising a manually movable spring-biased pivoted member having a finger-engaging surface and a coin slot through said surface, a coin carrier disposed adjacent said coin selector and having a coin-receiving pocket normally in registration with said coin slot, said coin carrier being arranged to be rotated by said coin selector to move said pocket to a coin-discharge position, structure including an arcuate coin track concentric with said coin carrier and arranged to retain a coin in said pocket while the coin carrier is in rotation, a coin gauge carried by said coin carrier and normally projecting radially from said coin carrier towards said coin slot and having a notch arranged to engage the edge of a coin, said coin gauge being retractible into said pocket and arranged to guide a coin from the coin slot into the pocket, said coin gauge normally projecting from the coin carrier sufficiently to obstruct partially said coin track structure unless retracted, and a cam operatively connected with the coin selector and rotatable by the same to re-

tract said coin gauge sufficiently to clear said coin track structure.

2. The combination according to claim 1 wherein said coin gauge is a lever fulcrumed on said coin carrier, one arm of said lever having a distal end portion extending transversely of the coin carrier, said distal end portion being notched and receiving the edge of a coin, a second arm of said lever being arranged to be engaged by said cam when the coin selector is depressed without a coin or token of suitable diameter having been passed through the coin slot.

3. The combination according to claim 1 wherein said coin gauge is a lever fulcrumed on said coin carrier, one arm of said lever having a distal end portion extending transversely of the coin carrier, said distal end portion being notched and receiving the edge of a coin, a second arm of said lever being arranged to be engaged by said cam when the coin selector is depressed without a coin or token of suitable diameter having been passed through the coin slot, and characterized in that said cam is coaxial with said coin carrier and rotatable relative thereto.

4. The combination according to claim 1, wherein said coin gauge is a lever fulcrumed on said coin carrier, one arm of said lever having a distal end portion extending transversely of the coin carrier, said distal end portion being notched and receiving the edge of a coin, a second arm of said lever being arranged to be engaged by said cam when the coin selector is depressed without a coin or token of suitable diameter having been passed through the coin slot, and characterized in that said cam is coaxial with said coin carrier and rotatable relative thereto, and including a bridge member pivotally mounted on and carried by said coin carrier and arranged to be moved and retracted by said cam, said bridge member normally projecting radially from said coin carrier and arranged to support coins in transit to said coin pocket.

5. The combination, in a coin controlled mechanism, of a chute, a coin carrier shiftable along said chute from a normal position to a discharging position to advance a coin therethrough, a carrier biasing spring normally urging said carrier toward its normal position, a power spring to urge the coin carrier toward its coin discharging position, a manually shiftable coin receiving member having a finger contacting surface of extended area and having a coin slot therethrough positioned within said surface so that the finger can push a coin through the coin slot and press against said surface in a single operation, said coin receiving member being movable in response to such pressure, means responsive to the movement of the coin receiving member to energize sequentially the power spring and to couple the power spring to the coin carrier whereby the power spring will overcome said biasing spring and drive the coin carrier from normal position to discharge position, and means responsive to predetermined movement of the coin carrier to uncouple the coin carrier from the power spring and cause the coin carrier to be returned to normal position by its biasing spring.

6. The combination in a coin-controlled mechanism, of a rotatable coin carrier, a manually movable member having a coin slot in registration with the coin carrier, a bridge member carried by and rotatable with said coin carrier and normally projecting therefrom toward the manually movable member to form a support for coins in transit to the coin carrier, a mechanical inter-

link between said manually movable member and said bridge member for transmitting motion from said manually movable member to said bridge member to retract said bridge member into said coin carrier, and means for actuating the coin carrier.

7. The combination in a coin-controlled mechanism, of a rotatable coin carrier, a manually movable member having a coin slot in registration with said coin carrier, a bridge member carried by and rotatable with the coin carrier and normally projecting radially therefrom toward said manually movable member to form a support for coins in transit to the coin carrier, a cam connected with and actuated by the manually movable member and provided with means for engaging said bridge member to move the same toward the center of rotation of the coin carrier and to retract the said bridge member, and means for rotating the coin carrier.

8. The combination in a coin controlled mechanism, of a rotatable coin carrier having a pocket for reception of a coin, a member manually movable toward said coin carrier and having a coin slot normally in registration with said pocket, a bridge member carried by and rotatable with said coin carrier and spring-biased so as normally to project radially from said coin carrier to form a support for coins in transit to the coin carrier pocket through said coin slot, a rotatable cam concentric with said coin carrier and arranged to engage and move said bridge member toward the center of rotation of said coin carrier to retract the bridge member, means for transmitting motion from the manually movable member to said cam and operative to rotate the same to effect retraction of said bridge member upon movement of the manually operable member toward said coin carrier, and means for rotating the coin carrier.

9. The combination in a coin-controlled mechanism, of a rotatable coin carrier having a pocket for the reception of a coin, a coin chute structure having an arcuate coin track concentric with said coin carrier and arranged to retain a coin in said pocket, a member manually movable toward said coin carrier and having a coin slot normally in registration with said pocket, a bridge member pivotally mounted on the coin carrier within said pocket and rotatable with said coin carrier, said bridge member normally projecting radially from said coin carrier and obstructing the coin chute structure to form a support for coins in transit to the coin carrier pocket, a rotatable cam concentric with said coin carrier and provided with means for engaging said bridge member upon rotation relative to said coin carrier to retract said bridge member and clear said coin chute structure, means for transmitting motion from the manually movable member to the cam for rotating the same to retract said bridge member, and means for rotating the coin carrier.

10. The combination according to claim 9, wherein the manually movable member is rotatable about a pivotal center and spring-biased away from the coin carrier.

11. The combination according to claim 9, wherein the manually movable member is rotatable about a pivotal center and spring-biased away from said coin carrier and said cam is operative to hold the bridge member in retracted position throughout the rotary movement of the coin carrier.

12. The combination according to claim 9,

characterized in that the bridge member includes a portion having an arcuately curved surface conforming to the peripheral curvature of a coin of the diameter to be received, which curved surface defines a wall of the pocket.

13. The combination according to claim 9, wherein the manually movable member is rotatable about a pivotal center and spring-biased away from said coin carrier, and said cam is operative to hold the bridge member in retracted position throughout the rotary movement of the coin carrier and includes a link which is pivotally connected at one end to the cam and pivotally connected at the other end to the manually movable member.

14. The combination in a coin controlled mechanism, of a coin receiving and inducting member having a finger contacting surface of extended area and having a coin slot therethrough positioned within said surface so that the finger can push a coin through the coin slot and press against said surface in a single movement, said member being yieldably movable in response to finger pressure exerted thereagainst, a rotatable coin carrier having a coin pocket normally in registration with said coin slot, a retractile bridge member carried by and rotatable with said coin carrier and normally projecting radially from said coin carrier to provide a support for coins in transit from the coin slot into the coin pocket, means operative in response to movement of said coin receiving and inducting member toward said coin carrier to retract said bridge member into said pocket, and means controlled by the coin receiving and inducting member and the coin for rotating the coin carrier.

15. The combination according to claim 14, including a cam mounted coaxially with and rotatable relatively to the coin carrier, and a link interconnecting the coin receiving and inducting member with said cam for effecting rotation thereof, said cam being operative upon rotation from its normal posture to move said bridge member to a retracted position.

16. The combination according to claim 14, including a cam mounted coaxially with and rotatable relatively to the coin carrier, and a link interconnecting the coin receiving and inducting member with said cam for effecting rotation thereof, said cam being operative upon rotation from its normal position to move said bridge member to a retracted position, and wherein said finger contacting surface is concave and the coin slot is centered in the concavity.

17. The combination in a coin controlled mechanism, of a pivoted coin receiving and inducting member having a finger contacting surface of extended area and having a coin slot therethrough positioned within said surface so that the finger can push a coin through the coin slot and press against said surface in a single movement, said coin receiving and inducting member being movable in response to such pressure, spring means for restoring said member to its normal position when the manual pressure thereagainst is released, a rotatable coin carrier disposed adjacent said member and having a coin receiving pocket which normally is in registration with said coin slot, said pocket being movable upon rotation of the coin carrier from its normal coin receiving position to a coin discharge position, spring means for rotating said coin carrier and means for coupling

said coin receiving and inducting member with said spring means for conditioning the same for rotation of the coin carrier and normally arranged in a non-coupling position and movable to coupling position by manual pressure applied to said coin receiving and inducting member, said coupling means including an element positioned for engagement by a coin inserted in said coin slot and movable by the coin to a coupling position wherein said coupling means is rendered effective to respond to a movement of said coin receiving and inducting member.

18. The combination according to claim 17, wherein said element is a rocker member carried by the coin receiving and inducting member and having a coin engaging portion situated adjacent one end of the coin slot and arranged to be rotated by a coin passing through the slot, said coupling means including a movable member arranged to be engaged by said rocker member when the latter has been rotated by the insertion of a coin in the coin slot to energize said spring means, said movable member being located beyond the path of movement of the rocker member when the latter is in its normal position.

19. The combination according to claim 17, including a spring actuated dog carried by the coin receiving and inducting member and arranged to latch the rocker member in position for energizing the spring means, and stop means arranged to engage said dog and move the same to release the rocker member immediately prior to the completion of each manually actuated movement of the coin receiving and inducting member whereby to disengage said dog from the rocker member.

20. The combination in a coin controlled mechanism, a coin carrier mounted for movement from a coin receiving position to a coin discharging position, a manually movable member having a coin slot in registration with the coin carrier, a bridge member carried by and movable with the coin carrier and normally projecting therefrom toward the manually movable member to form a support for a coin in transit to the coin carrier, means for transmitting movement from the manually movable member to said bridge member to retract said bridge member into said coin carrier, and means for actuating said coin carrier to move the same from its coin receiving position to its coin discharging position.

21. The combination in a coin controlled mechanism, of a rotatable coin carrier provided with two sectors having mutually staggered teeth, a power spring operatively connected with the coin carrier for rotating the same, a coin selector having a coin slot, means arranged to be engaged by the coin selector and a coin inserted therein for energizing the power spring, and two pivoted escapement oscillators each provided with a pair of detents positioned to be engaged alternately by the teeth of said sectors, the oscillators being rocked non-synchronously by the sector teeth and each oscillator being extended at each end beyond the detents, the aggregate inertia of the oscillators imposing restraint on the speed of rotation of the coin carrier.

22. The combination, in a coin controlled mechanism, of a coin carrier shiftable between a coin receiving position and a coin discharging position, a carrier biasing spring normally urging said carrier toward its coin receiving position, a power spring to urge the coin carrier toward its coin discharging position, a manually shiftable coin receiving member having a finger contacting sur-

face of extended area and having a coin slot therethrough positioned within said surface so that the finger can push a coin through the coin slot and press against said surface in a single operation, said coin receiving member being movable in response to such pressure, means responsive to the movement of the coin receiving member to energize sequentially the power spring and to couple the power spring to the coin carrier whereby the power spring will overcome said biasing spring and drive the coin carrier from coin receiving position to coin discharging position, and means responsive to predetermined movement of the coin carrier to uncouple the coin carrier from the power spring and cause the coin carrier to be returned to coin receiving position by its biasing spring.

23. In a coin controlled mechanism, the sub-combination of a coin receiving member having a finger contacting surface of extended area and having a coin slot therethrough positioned within said surface so that the finger can push a coin through the coin slot and press against said surface in a single movement, said coin receiving member being movable in response to such pressure, a power spring, a coin carrier shiftable between a first position and a second position, means interconnecting the coin receiving member and the power spring and movable with movement of the coin receiving member to energize the power spring, means operable upon predetermined movement of the interconnecting means to connect the carrier to the energized power spring to

10
